ABSTRACT OF THE DISCLOSURE

A timepiece bearing having a drilled jewel and an end piece which is held adjacent to the back of the drilled jewel. The end piece has at least one radial notch at its periphery which extends into the central portion of the end piece and exposes corresponding portions of the drilled jewel allowing the bearing to be lubricated without removal or dismantlement.

The present invention relates to timepieces generally and more specifically to bearings for timepiece pivots either of the shock-absorbing type wherein a drilled jewel and an end piece are held in place at a small distance from each other by a spring, or of the "capped-jewel" type wherein a drilled jewel and an end piece are set at a slight distance from each other in a mount or setting.

Today the technique of cleaning timepieces or watches by ultrasonics allows a watch repairman to clean a watch without disassembling the watch movement. However, although cleaning modern bearings is possible without disassembling the entire watch movement, this is not true for oiling the bearings after the cleaning. In order to cause a drop of oil to penetrate between the drilled jewel and the end piece of the bearings, the bearings must be taken apart. Thus, there has been an increasing demand for bearings, both of the "capped-jewel" and of the shock-absorbing type, which can be oiled in assembled condition.

One way to provide a bearing which can be oiled in assembled condition is to construct the bearing such that the end piece has a smaller diameter than its associated drilled jewel. Such constructions are illustrated in my copending application Ser. Nos. 704,826 and 704,827 which show, in one case, the small diameter end piece supported at a slight distance behind the drilled jewel by a spring having an oil opening and, in the other case, the small diameter end piece supported at a slight distance behind the drilled jewel in a mount having an oil opening. These bearings described in my copending application require special springs or mounts to hold the small end piece.

The timepiece pivot bearing, either of the "capped-jewel" and the shock-absorbing type, to which this present invention pertains, comprises a bearing body, a drilled, or holed, jewel and an end piece, sometimes referred to as an end jewel or an end stone. In the shock-absorbing bearing the drilled jewel is press-fitted into the bearing body which has an annular mount, and the end piece, in the form of a flat disc, is held by a spring at a small distance from the drilled jewel. In the "capped-jewel" bearing, the drilled jewel and the end piece are both set in an annular mount or setting at a small distance from each other.

This timepiece pivot bearing to which this present invention pertains is characterized by the fact that the end piece of the bearing, whose diameter is of conventional size, that is, about the same size as or greater than the diameter of its corresponding drilled jewel, has at its periphery at least one notch which extends radially almost to the center of the end piece to enable a drop of oil to

2

be deposited between the two jewels of the bearing without disassembling the bearing. This drop of oil is drawn in between the drilled jewel and the end piece of the bearing towards the hole of the drilled jewel and is retained there by capillary action.

5 The object of the present invention is to provide a simplified bearing structure of either the "capped-jewel" or shock-absorbing type which can be cleaned and also reoiled without being taken apart.

Another object of this invention is to provide bearings 10 for timepiece pivots of the type having a drilled jewel and an end piece which can be cleaned and also reoiled without being taken apart wherein the diameter of the end piece is conventional in size, that is, about the same size as or greater than the diameter of its corresponding drilled jewel, and wherein the need for special mounts or springs to hold the end piece is eliminated.

Other objects and features of the invention will become apparent to those skilled in the art as the disclosure is made in the following description of the invention as illustrated in the accompanying drawing in which:

FIGURE 1 is an axial section through a shock-absorbing bearing constructed in accordance with this invention;

FIGURE 2 is a plan view of the bearing shown in FIGURE 1;

FIGURE 3 is a partial view in larger scale showing the end piece and spring of the bearing shown in FIGURE 1;

FIGURE 4 is an axial section through a shock-absorbing bearing constructed in accordance with this invention illustrating another embodiment of this invention;

FIGURE 5 is a plan view of the bearing shown in FIGURE 4;

FIGURE 6 is an axial section through a "capped-jewel" bearing constructed in accordance with this invention;

FIGURE 7 is a top-plan view of the bearing shown in FIGURE 6;

FIGURE 8 is an elevational view of the bearing shown in FIGURE 6.

40 FIGURES 9, 10, and 11 show various shaped end pieces used in bearings constructed in accordance with the present invention.

The bearing shown in FIGURES 1-3 is a shock-absorbing bearing for balance staff pivot. It comprises a bearing body 1 in which there rests freely on a conical bearing surface an annular mount 2 with conical upper portion 2'. Drilled jewel 3 is press-fitted in the annular mount 2. The drilled jewel 3 with its mounts 2, 2' swings making it possible in a known manner to absorb the radial shocks which a balance staff pivot (not shown) may incur.

An end piece, or end jewel, or stone 4, consisting of a cylindrical disc having a diameter larger than that of the drilled jewel 3, is held elastically on an inner shoulder of the upper conical portion 2' of the mount 2 by a lyre-shaped spring 5 removably held in a known manner in a transverse passage of

60 shape in the bearing body 1.

The end stone 4 has a radial notch 6 of trapezoidal, or rectangular, shape at its periphery which, as viewed from above by one oiling the bearing, uncovers a corresponding sector of the drilled jewel 3. The notch 6 extends almost to the center of the end piece, and a drop of oil can be introduced through this notch from above, by means of an oil-pipe for example, into the area between the two jewels without dismounting the bearing. To insure that the drop of oil is drawn towards the axial hole of the drilled jewel 3, and that it is held there by capillary action, it is advisable, in practice, to position the point at the end of the

notch that is closest to the center of the end piece at a distance d from the center of the end piece which is equal to 2 to 4 times the minimum radius of the hole of the drilled jewel.

In the embodiment shown in FIGURES 1-3, the end stone 4 can turn in its seat as a result of impact or ultrasonic cleaning. Therefore, after rotation due to impact or cleaning, the notch 6 of the end piece might occupy any angular position. It might, for instance, be in the position shown in FIGURE 3, that is, below the arm 5' of the spring 5. Thus, it is important that the shape and dimensions of the notch, as well as the shape and dimensions of the portion 5' of the spring, be such that the end piece cannot escape from the spring as a result of shifting due to a shock and to insure that the bearing, with its shock-absorbing function, remains intact.

Also, it is desirable when the end stone is positioned so that the arm 5' of the spring covers the notch 6, that the shape and the dimensions of the portion 5' of the spring, as well as those of the notch, be such that the notch is only partially covered and that lubrication is still possible.

In the embodiment of FIGURES 4 and 5, the notch 16 is arc-shaped. The lyre spring 15 has an extending tab on each side of the axis X-X which is bent towards the drilled jewel and extends into the notch 16 to prevent the end piece, or end stone, 14 from turning. In this way the end piece, or stone, 14 is prevented from accidentally arriving in a position which permits the notch to free itself from the spring.

Of course, it should be noted that the end piece may have more than one notch, for instance two diametrically opposite notches, and that the shape of the notches may differ from those shown in FIGURES 3 and 5.

The "capped-jewel" shown in FIGURES 6, 7 and 8 comprises an annular bearing body 21 in which there is press-fitted in the lower portion a drilled, or holed, jewel 22 and in the upper portion a disc-shaped end piece, or end jewel, or stone, 23 having a diameter larger than the diameter of the drilled jewel. This end piece is held at a slight distance from the drilled jewel by an annular shoulder 21 of the bearing body.

The end stone 23 has at its periphery two diametrically opposite radial notches 24 of trapezoidal, rectangular, triangular, or other suitable shape which, as viewed from above by a person oiling the bearing, uncover corresponding sectors of the drilled jewel 22. Each notch 24 penetrates almost to the center of the end piece. A drop of oil can be introduced through either of these notches from above, by means of an oil-pike for example, into the area between the two jewels without disassembling the bearing. To insure that the drop of oil is drawn towards the axial hole of the drilled jewel 22 and that it is retained there by capillary action, it is advisable, in practice, to position the point at the end of each notch which is closest to the center of the end piece at a distance d from the center of the end piece which is equal to 2 to 4 times the minimum radius of the hole of the drilled jewel.

Although the bearing shown makes oiling possible without disassembling the bearing, it may be desirable for some reason to remove the end piece. To provide for the removal of the end piece, the bearing body 21 is provided with a diametral passage 25 which permits the point of a tool to be introduced between the end piece and the drilled jewel to force the end piece out from the bearing body.

The variant embodiments of the end piece shown in FIGURES 9 and 10 have only single radial notches 26, and 27, respectively. The variant shown in FIGURE 11 has two notches 28 of generally "U" shape. These FIGURES 9, 10, and 11 show only a few of the various notches that may in fact be employed. Thus, it should be realized, of course, that these notches, are only illustrative and that the number and shape of the radial notches may differ from those shown without departing from this invention.

The invention has been described hereinabove in preferred embodiments, but it is to be understood that the invention is in no way confined to the particular embodiments shown and described and that numerous modifications or alterations may be made therein without departing from the spirit of the invention.

I claim:

1. A bearing for a timepiece pivot comprising a drilled jewel and an end piece held at a slight distance from said drilled jewel, a bearing support structure for holding said drilled jewel and said end piece in spaced relationship, said drilled jewel and said end piece defining a space therebetween to receive oil, said end piece having at least one notch at its periphery extending into its central portion, said notch exposing portions of said drilled jewel and defining an opening leading from the top and side of said end piece into said space between said drilled jewel and said end piece, whereby oil can be deposited through said opening into said space between said drilled jewel and said end piece without disassembling the bearing.
2. A bearing for a timepiece pivot as described in claim 1 wherein said end piece has two notches.
3. A bearing for a timepiece pivot as described in claim 1 wherein said notch of said end piece is generally U-shaped.
4. A bearing for a timepiece pivot as described in claim 1 wherein said notch of said end piece is generally trapezoidal.
5. A bearing for a timepiece pivot as described in claim 1 wherein said end piece is circular and the edge of said notch of said end piece is defined by an arc.
6. A bearing for a timepiece pivot as described in claim 1 wherein said end piece is circular and the edge of said notch of said end piece is formed by a chord.
7. A bearing for a timepiece pivot as described in claim 1 wherein said end piece has a diameter substantially the same as the diameter of said drilled jewel.
8. A bearing for a timepiece pivot as described in claim 1 wherein said end piece has a diameter greater than the diameter of said drilled jewel.
9. A bearing for a timepiece pivot as described in claim 1 wherein the end of said notch is located at a distance from the center of the end piece equal to 2 to 4 times the minimum radius of the hole of the drilled jewel.
10. A bearing for a timepiece pivot as described in claim 1 wherein said bearing support structure includes a mount, said end piece and said drilled jewel being press-fitted in said mount and being held thereby at a slight distance apart.
11. A bearing for a timepiece pivot as described in claim 10 wherein said mount is annular and said end piece is disc-shaped.
12. A bearing for a timepiece pivot as described in claim 10 wherein said bearing body is provided with a radial passageway which permits the point of a tool to be introduced between the end piece and the drilled jewel to force out the end piece.
13. A bearing for a timepiece pivot as described in claim 10 wherein said end piece has two generally U-shaped notches at its periphery.
14. A shock-absorbing bearing for a timepiece pivot as described in claim 1 wherein the bearing support structure includes a mount, said drilled jewel being press-fitted in said mount, and a spring, said end piece being held by said spring at said slight distance from said drilled jewel.
15. A shock-absorbing bearing for a timepiece pivot as described in claim 14 wherein said mount is annular, said end piece disc-shaped, and said notch in said end piece extends radially almost to the center of said end piece.
16. A shock-absorbing bearing for a timepiece as described in claim 14 wherein said spring has two extending tabs which are bent towards the drilled jewel and

which extend into the notch to contact the sides of the notch when the end piece moves whereby the end piece is prevented from rotating.

17. A shock-absorbing bearing for a timepiece pivot as described in claim 14 wherein said spring contacts the surface of said end piece to hold it at a slight distance from said drilled jewel and wherein said end piece can move with respect to said spring into a position such that said notch is beneath said spring, said spring being adapted to transverse said notch and to contact at least one surface adjacent said notch when said notch moves into said position such that said notch is beneath said spring, whereby the end piece is held by said spring when said notch is beneath said spring.

18. A shock-absorbing bearing as in claim 17 wherein said end piece can rotatably move with respect to said spring, said rotation being caused by shock or by cleaning.

19. A shock-absorbing bearing as in claim 17 wherein said spring is adapted to transverse said notch over an

area smaller than the area of the notch whereby a portion of the notch remains exposed allowing for the introduction of oil into said space between said drilled jewel and said end piece.
